DISPLAY FIXTURE

Henry A. Jenkins, Fayetteville, N. C.

Application September 22, 1937, Serial No. 165,206

3 Claims. (Cl. 211—2)

The invention relates to a display fixture and more especially to a display stand or table.

The primary object of the invention is the provision of a fixture of this character, wherein the same involves a table carrying a removable top section and in this table is a convertible rack enabling the display of merchandise in a unique and selected manner, the fixture being usable in mercantile establishments for the display of merchandising goods.

Another object of the invention is the provision of a fixture of this character, wherein the construction thereof is novel in its entirety and is susceptible of use in mercantile establishments for the display of varying kinds and conditions of merchandise, being readily adjustable for this purpose.

A further object of the invention is the provision of a device of this character, which is simple in its construction, unique in its make-up, thoroughly reliable and efficient in operation, neat in appearance, and inexpensive to manufacture.

With these and other objects in view, the invention consists in the features of construction, combination and arrangement of parts as will be hereinafter more fully described, illustrated in the accompanying drawings, which disclose the preferred and modified forms of embodiment of the invention and pointed out in the claims hereunto appended.

In the accompanying drawings:

Figure 1 is a perspective view of the fixture constructed in accordance with the invention.

Figure 2 is a vertical sectional view taken on the line 2—2 of Figure 4 looking in the direction of the arrows.

Figure 3 is a bottom plan view with the legs of the fixture removed.

Figure 4 is a plan view with the top removed and partly broken away.

Figure 5 is a vertical transverse sectional view showing the legs removed.

Figure 6 is a perspective view of one of the legs of the fixture.

Figure 7 is a perspective view of a modified form of construction.

Figure 8 is a view similar to Figure 7 showing the fixture in an adjusted position.

Figure 9 is a view similar to Figure 8 with the legs removed.

Figure 10 is a view similar to Figure 9 showing a further modification of the fixture.

Figure 11 is a view similar to Figure 10 showing a further modification.

55 Similar reference characters indicate corre-

sponding parts throughout the several views in the drawings.

Referring to the drawings in detail, particularly Figures 1 to 6 inclusive, the fixture designated generally at A involves a body frame 10 having generally at A involves a body frame 10 having 5 at the corners thereof short leg formations provided with leg sockets 11 partially strap-like for receiving the male tenons 12 of separable relatively long supporting legs 13. This frame 10 has a permanent bed 14 provided marginally at three 10 sides thereof with an upstanding flange-like rim 15 while the remaining non-rimmed side of the bed 14 has swingingly connected thereto a rack hereinafter fully described.

The rack involves the sections 16 and 17, respectively, these being interfitting with each other following the curvature cut 18 and are swingably connected by pivot pins 19 in their interfitting relation to each other while the section 16 is connected by hinges 20 to the non-rimmed side 20 21 of the bed 14. These sections 16 and 17 when in a flat condition in the same plane with each other are housed within a pocket 22 formed by the rim 15 on the bed 14 in the latter.

On the section 17 at the under side thereof is 25 loosely coupled at 23 a combined handle and prop 24 workable through a clearance 25 in the bed 14, being suspended beneath the bed when the sections 16 and 17 are lying flat within the pocket 22 and when the sections 16 and 17 are 30 raised and adjusted in a folded relation to each other the member 24 can function as a prop giving the required slant thereto and engageable with the bed 14 at the upper face thereof. The sections 16 and 17 constitute a rack for displaying merchandise while the pocket 22 is susceptible of carrying merchandise therein and for displaying the same.

Telescopically fitted over the bed 14 and the rim 15 thereof when the sections 16 and 17 are 40 lowered into the pockets 22 is a removable top or cover section 26 so that the fixture is convertible into a table or stand.

In Figures 7 to 10 inclusive, of the drawings, there are shown modifications wherein the 45 hinged sections 27 and 28 are adapted for interfitting with each other while the section 28 carries the arms 29, one of these sections 27 being hinged at 31 to the bed 32 while the section 28 is free thereof but is propped 50 thereon.

In Figure 11 of the drawings there is shown a further modification wherein the section 33 is hinged at 34 and adjustably connected with this section is a brace 35, which is swingable at 36 on 55

the stand, and the section 37 interfitted and pivoted at 38 with the section 33, can swing into engagement with a keeper groove or channel 39 in the upper face of the bed 40, the bed 32 being 5 also provided with a keeper channel or groove 41 corresponding to the channel or groove 39 enabling the convertible racking of the sections 27 and 28 and 33 and 37, respectively, these sections just mentioned being also pocketed within 10 the fixture or stand when not in use.

The merchandise or goods to be displayed is carried by the section constituting the rack hereinbefore set forth.

With reference to the member 24, it can be 15 used as a handle to lift the sections from the pocket within the stand by pushing upwardly upon such member beneath the bed of the stand and thereby raising the sections from within the pocket of the latter.

20 The legs 13 are removable so that the height of the stand can be changed as should be apparent from Figures 1, 2, 5, 9, 10 and 11 of the drawings.

What is claimed is:

- 25 1. A display fixture comprising a body frame formed with a permanent bed, a rack having sections swingably interfitting each other, hinges swingably connecting one of said sections to the body frame, the other of said sections being cut and shaped for effecting a reversible prop for the section hinged to the frame and engageable with the permanent bed when in reversed positions to the said hinged section, and a swingable weight element carried by the reversible prop section and movable through the permanent bed when said sections are in the same plane with each other and resting flat against the said permanent bed, and a rim on the body frame for pocketing the rack when the sections are in the same plane with each other and resting flat upon the permanent bed of said body frame.
- 30 2. A display fixture comprising a body frame formed with a permanent bed, a rack having sections swingably interfitting each other, hinges swingably connecting one of said sections to the body frame, the other of said sections being cut and shaped for effecting a reversible prop for the section hinged to the frame and engageable with the permanent bed when in reversed positions to the said hinged section, a swingable weight element carried by the reversible prop section and movable through the permanent bed when said sections are in the same plane with each other and resting flat against the said permanent bed, and a rim on the body frame for pocketing the rack when the sections are in the same plane with each other and resting flat upon the permanent bed of said body frame.
- 35 3. A display fixture comprising a body frame formed with a permanent bed, a rack having sections swingably interfitting each other, hinges swingably connecting one of said sections to the body frame, the other of said sections being cut and shaped for effecting a reversible prop for the section hinged to the frame and engageable with the permanent bed when in reversed positions to the said hinged section, a swingable weight element carried by the reversible prop section and movable through the permanent bed when said sections are in the same plane with each other and resting flat against the said permanent bed, and a rim on the body frame for pocketing the rack when the sections are in the same plane with each other and resting flat upon the permanent bed of said body frame, the said permanent bed having a seat for the engagement of the reversible prop section when in propping relation to the other section of said rack.

HENRY A. JENKINS.
